UNITED STATES PATENT OFFICE.

DUNCAN ROBINSON, OF ATLANTIC CITY, NEW JERSEY.

GOLF TEE.

Application filed June 23, 1924. Serial No. 721,780.

To all whom it may concern:

Be it known that I, DUNCAN ROBINSON, a citizen of the United States, residing at Atlantic City, in the county of Atlantic and 5 State of New Jersey, have invented an Improvement in Golf Tees, of which the following is a specification.

This invention relates to golf tees and has for its object to provide a tee composed of 10 flexible and yielding material having means associated with it to impede the flight of the tee when it is struck accidentally in the act of striking the golf ball supported by it.

Fig. 1 is a plan view of the tee embodying 15 the invention.

Fig. 2 is a reverse view of Fig. 1.

Fig. 3 is a vertical section of the tee and illustrating the manner of its use.

Fig. 4 is a side elevation of the tee and a 20 golf ball supported by it.

Fig. 5 is a view illustrating the manner in which the drag or damper opposes the flight of the tee.

Fig. 6 is a view similar to Fig. 5 but 25 illustrating a tee provided with a plurality of dampers arranged in tandem.

As here shown, the tee embodying the invention comprises the approximately semi-spherical or convex tee 10 having the hollow 30 or concave interior 11 and the broad open base 12 and a side wall 13 composed of light and resilient material, as soft rubber. Said tee is formed with a relatively small top opening 14 which is adapted to form a seat 35 for the golf ball, as shown in Figs. 3 and 4.

As thus arranged, the tee may be impelled a considerable distance when accidentally struck by a golf club in the act of striking the ball. It is an object of this invention 40 to provide the tee with means to retard its flight through the air when accidentally struck, and limit the flight to a comparatively short distance. To this end I provide the tee with a damper or drag 15, which 45 damper, preferably, is a portion of an approximate sphere, or is concave on one side and has a convex opening 16 therein and has a wall 17 formed of some light and preferably soft and resilient material, as soft rubber. Said damper is attached to the tee by 50 a flexible connection as the cord 18, which cord is of substantial length, say about four or five inches. Said cord may be attached to the tee in any suitable manner but, preferably is attached to, as by passing through, 55 the side wall thereof near the base-edge

thereof and extends from the inner face of said wall and outwardly through the open base. The cord may be attached to the damper in any suitable manner but preferably the attachment is such that, in flight, the concave face, or opening, of the damper is presented in the direction of flight, whereby the damper offers its maximum resistance to flight, by reason of its concavity. The 60 connection between said cord and the damper may be through the three approximately equally spaced strands 20, which strands may pass through the damper in the vicinity of its edge, whereby to hold the damper to 65 assume the position shown in Fig. 5 in flight, or as a parachute.

When the tee is used to support a golf ball, the construction is such that the damper and its connecting cord may be stowed away 70 within the hollow interior of the tee, as illustrated in Fig. 3 and, for this purpose, the damper is smaller than the tee.

The device has been found to be very effective in use, and the tee is restricted to 75 but relatively short flights when struck.

If desired, I may provide the tee with a plurality of dampers arranged preferably in tandem, as illustrated in Fig. 6; and the end 80 damper may be the smallest in size.

The construction of the tee, also, is such that it offers, alone, considerable resistance to flight.

Extensive use of this golf tee has shown the following:—This tee offers no appreciable obstruction to the free swing of the club nor to the accuracy of the stroke, as an awkward or weighted "tee" must necessarily do. Should the club-head hit the "tee" while making the stroke, the "tee" will 90 move freely, but, due to its lightness and shape, the movement will be limited and as it will be in the same direction as the flight of the ball, the player may readily recover the "tee" as he proceeds towards his ball. Should 95 the stroke be clean and true, the "tee" will be found not to have moved from the position in which it was placed. The tee is so arranged that it will support the ball properly regardless of the character of the surface on which the tee rests.

I claim:

1. As an article of manufacture, a golf tee comprising a light, hollow support of resilient material having a broad open base 110 and a small top shaped to form a seat for a golf ball, a damper arranged to move with

- and resist the flight of said tee and composed of light, resilient material and shaped to offer maximum resistance to movement through the air in one direction, and a flexible cord of substantial length connecting said tee and damper, said cord having a connection with the damper to hold it in position to present its maximum resistance to flight.
2. As an article of manufacture, a golf tee comprising a light, hollow and approximately semi-spherical support of resilient material having a broad open base and a small open top adapted to form a seat for a golf ball, a damper arranged to move with and resist the flight of said tee and composed of light, resilient material and shaped to offer maximum resistance to movement through the air in one direction, and a flexible cord of substantial length connecting said tee and damper, said cord having a connection with the damper to hold it in position to present its maximum resistance to flight, said tee constructed and arranged to receive said damper and cord within its hollow interior.
3. As an article of manufacture, a golf tee comprising a light support of resilient material having a broad base and a small top adapted to form a seat for a golf ball, a damper arranged to move with and resist the flight of said tee and composed of light, resilient material and having a concave face, and a flexible cord of substantial length connecting said tee and damper and having a connection with said damper to present the concave face thereof in the direction of flight.
4. As an article of manufacture, a golf tee comprising a light hollow support of resilient material having a broad open base and a small top shaped to form a seat for a golf ball, and a plurality of dampers connected flexibly in spaced tandem relation with and to each other and said tee, said dampers arranged to move with and oppose the flight of the tee.
5. As an article of manufacture, a golf tee comprising a light hollow support of resilient material having a broad open base and a small top shaped to form a seat for a golf ball, a light damper adapted to move with and resist the flight of said tee having a flexible connection of substantial length with said tee, said damper being smaller than said tee and adapted, with its connection, to be contained within the hollow interior of said tee.
6. As an article of manufacture, a golf tee comprising a light hollow support of resilient material having a broad open base and a small top shaped to form a seat for a golf ball, a damper arranged to move with and oppose the flight of said tee, said damper composed of light material and having a concave face and a convex hollow and open interior, a flexible connection extended between said damper and tee and having a triple connection with the damper, which connection is arranged to maintain the concave interior of said damper presented in the direction of flight.
7. As an article of manufacture, a golf tee comprising a light hollow support of resilient material having a broad open base and a small top shaped to form a seat for a golf ball, a light damper arranged to move with and oppose the flight of said tee, and a flexible cord of substantial length connecting said damper and tee, said cord extended into the interior of said tee through the open base thereof and having a connection with said tee within said base.

In testimony whereof, I have signed my name to this specification.

DUNCAN ROBINSON.
